SAWYER'S INDICATOR FOR SAWMILL LOG CARRIAGES.

Application filed August 19, 1926 Serial No. 180,334.

Our invention relates to saw mills, and has for its object generally, the production of an indicator which will clearly and unmistakably indicate to a head sawyer occupying his operative station not only the thickness of the cut from the log which the log carriage is set for the saw to make, but also, what is more important, the thickness of the log which remains uncut, it being of importance for economical reasons, to cut a log as close as may be to its maximum capacity, with due allowance, in the cutting, for the kerfs of the saw.

Prior to our invention, the cut of the saw upon a log on the log carriage was exclusively determined and fixed by a workman designated as a setter, whose duty it is to set the log in relation to the saw, so as to obtain a predetermined thickness of cut. This is work which requires a high degree of skill and accuracy of performance on the part of the setter, since upon it depends, in a large measure, the quality of the output of the mill, and because the variation of even a small fraction of an inch in the setting of the log may result in loss which may be serious. The cause from which such loss results primarily is, of course, a mistake made by the setter in the setting of the log, but oftener it occurs that a greater loss results from the attempt of the setter to cover up his mistake by dividing the loss from an overcut by apportionment of it among subsequent cuttings from the same log, with the result of throwing all subsequent measurements out of true.

The consequence, in either of said instances, is to produce a variation of cut which when it is discovered as it must be eventually, must result in rejection or a degrading, of a loss, not only of the first board or piece severed from the log but also of all boards or pieces subsequent to the first error. For example, if the log is set to cut a series of boards of one inch thickness, a variation of a small fraction in the thickness of a board will disqualify it for passage through a planer, for instance, with loss to the mill, and any attempt to cover up the variation of a preceding cut will disqualify each subsequent cut, with proportionate increase of loss, especially if the thickness of board produced through error is of an odd size.

The method of communication which is necessary between the sawyer and the setter

has been exclusively by an exchange of visible signals, usually manual, and is far from satisfactory. Even such means of communication can convey no information to the sawyer that the setter's work is properly done, and especially no information of the setter's subsequent attempt to conceal his error if made. In the employment of said method, it was only in the final measurement of the lumber that the error could be detected.

By our invention, a sawyer has constantly presented to his eye, by an accurate mechanical instrument, an indication which constitutes a telltale or check on the work of the setter in setting of the log carriage, which the sawyer may rectify, if need be, before he sets his carriage in motion.

Our indicator should afford accurate means which will enable the sawyer to detect a setter's mistake at a glance. Its indication is therefore preferably magnified, in effect, as through the employment of a register of fractional parts of a cut, without material increase of the dimensions of the indicator proper.

What constitutes our invention will be hereinafter specified in detail and succinctly defined in the appended claims.

In the accompanying drawings, wherein our invention is illustrated in present preferred form of embodiment.

Figure I is a front elevation, partly in section, of one of our indicators in operative communication with a log carriage whereof a portion is shown in side elevation.

Figure II is a view similar to Figure I but taken at right angles thereto, and showing the log carriage partly broken away to accommodate the scale of the drawing. 95

Figure III is a top plan view, with inferior construction exposed, of the indicator and its carriage connection.

Referring to the numerals on the drawings, 1 and 2 indicate the side frame pieces, 100 and 3 indicates one of the cross pieces of an ordinary log carriage, which is supported, for example, as usual, on wheels 4, which, in operation, travel on usual track rails 5.

Mounted transversely upon the side frame pieces 1 and 2 of the log carriage, is fixed the usual complement of bed plates 6, of which the head or foremost one is shown in the drawings. Each bed plate 6 is channeled longitudinally for the accommodation 105

of a corresponding tongue 7, which is fixed to and projects from the bottom of the horizontal portion 8 of a knee 9.

The tongue 7 is preferably provided, as by provision of channels 10 on opposite sides of it, with a head 11, which, by aid of oppositely disposed strips 14 and 15, serves to hold the knee portion 8 firmly but slidably upon the bed plate 6, the said strips being bolted or otherwise securely fastened to the bed plate on its opposite sides, respectively.

Each knee 9, being, as by means just specified, for example, mounted on its bed plate, is provided with an upright 16, a plurality of knees being provided for each carriage.

The full complement of knees is subjected, by suitable mechanism for the purpose that is common in the art and, therefore, needs no illustration or description, to manipulative control from one point, at the will of the setter.

A log 18, made ready to be sawed by being first subjected to the usual slabbing operation, is laid lengthwise upon the bed plates, and is snugly set against the aligned series of knee uprights 16, by whose synchronous movement in unison it may be advanced step by step towards the saw 19, shown as circular in Figure II. The extent of movement of the knees in each setting of them determines, by the transverse movement they impart to the log, the thickness of the board or piece which the saw will cut from the longitudinally oncoming log.

The setting of the log for each cut fixes a line of departure from which the capacity of the remaining portion of the log to be sawed may be measured with practical precision.

Our invention is designed and adapted to enable a sawyer to determine in one and the same observation the two important items of information referred to in the last two sentences, but especially the latter, and thereby to regulate, to material economical advantage as above explained, the doing of his work.

Hitherto this specification has related to mechanism common in the art. We now proceed, with necessary regard thereto, to describe our invention in its present preferred form of embodiment, as illustrated in the drawings.

In its generic aspect our invention is held to comprehend broadly an indicator which will, in a single operation, accurately indicate the plane of each successive cut of a saw in a log, and for each successive cut will not only afford substantially exact advance information of the thickness of the piece that is severed from the log, but also, especially, of the thickness of the uncut portion of the log, thereafter remaining.

In the specific form of embodiment of our invention illustrated, 20 designates an indi-

cator case which may be of any preferred shape and dimensions, and which is, at the commencement of each cut, located in fixed position at any convenient point within reach of the clear vision of the sawyer when he is occupying his proper station at the head of the carriage.

The case 20 is, to the end proposed, securely fixed to the log carriage, as upon a beam 21 projecting from and fixed to the carriage in suitable propinquity to its head or foremost bed plate 6.

The case 20 is provided, preferably near its upper end, with oppositely disposed coaxial journal bearings 22 and 23 in which is rotatably mounted a shaft 24. Upon the shaft 24, next to the bearing 22, is confined a loose hub 26 that is coaxial and interior to a pulley rim 27, which projects rearwardly from a coaxial dial plate 28, whose face is provided with a peripheral annular zone 30. Said zone is inscribed with a series of regular graduations indicated by radially disposed lines 31. The number of graduations 31 indicates in terms of units of measurement, say inches, the distance of the entire travel of the knees upon their respective bed plates 6.

As illustrated, for example, the number of the graduations 31 is sixty, which means that the full log capacity of the log carriage to which it is appropriate is sixty inches. Consequently the graduations of the zone 30 are adapted to register in inches every adjustment applied to logs of sixty inch maximum thickness or to any thickness of log less than sixty inches, but the capacity of the log carriage and consequently of the indicator may be, of course, varied at pleasure.

The pulley rim 27 is in operative communication with the head knee 9, preferably through the instrumentality of a flexible member or substantially non-extensible rope 33. One end of the said rope is fastened, as indicated at 34, to the rim 27 about which, from the point 34, it makes substantially one complete turn, terminating in a vertical stretch 35 that drops tangentially from the point 34, approximately. The stretch 35 of the rope 33 is bent at its lower portion about a guide pulley 37, revolubly mounted in a support 38 that is fixed to the log carriage, as on the beam 21. Beyond the pulley 37, the end 40 of a taut horizontal stretch of the rope 33 is adjustably secured, as by an eye-bolt 41, to a stud 42 which projects from the adjacent side of the head knee 9, preferably from the horizontal portion 8 thereof. The function of the rope 33 is to impart to the pulley rim 27, with its attached dial plate 28, rotative movement proportionate to the horizontal movement, in one direction, of the knee 9, until such time as the limit of its movement is reached.

The pulley rim 27 also carries, in like

manner as it carries the rope 33, a flexible member or rope 45 which is wound upon the pulley rim in the direction of winding reverse to the winding of the rope 33 thereon. Consequently, as the rope 33 unwinds from the rim 27 the rope 45 winds upon it, and contrariwise.

One end of the rope 45, as indicated at 46, is fixed, like the end of the rope 33, to the pulley rim 27. Its free end depends tangentially from the pulley rim 27, and terminates in a loosely encased counter-weight 47, that is heavy enough to rotate the said rim by gravity whenever the opposing tension on the rope 33 is relieved. Consequently, the ropes 33 and 45, respectively, are kept taut by the cooperative tensions upon them imposed by the gravity of the counter-weight 47, and ready, respectively, to rotate the pulley rim 27 in opposite directions as often as occasion requires. Tension upon the rope 33, imparted by the pull of the knee 9 on it, keeps winding the rope 45 upon the pulley rim 27 until the limit of movement of said knee is reached. Thereupon, when the knee is receded to accommodate the reloading of the log carriage, the counter-weight 47 operates to restore the zone 30 to its starting position, when the operation described is ready to repeat itself.

The indicator, including the dial plate 28, as we have described it hitherto without restriction of its dimensions, is, in conjunction with a fixed pointer 50 on the case 20, a machine complete in itself, and, to a certain extent, that is to say under favorable conditions of use, practicable and useful without any addition to it; but we prefer to employ, in connection with what has been already specified, means for registering fractional parts of an inch, which is assumed, for example, to be the unit of measurement represented by the graduations 31 on the zone 30, by aid of what may be designated a fraction-indicating dial 51.

The function of the dial 51 is to indicate on a highly magnified scale, in effect, variation of the set of the log carriage in terms of minute fractional parts of an inch, or other unit of measurement that might be adopted. This result we accomplish without enlarging the dimensions of the dial plate 28, which is, of itself, an important consideration. To accomplish the result desired, we prefer to employ the mechanism next hereinafter specified.

The dial 51, aforesaid, is provided with a hub 52 which is fixed to the forward end of the shaft 24, and serves to secure revolvably thereon the hub 26. To that end of the shaft 24 which is opposite the hub 52, is fastened a pinion 54, which meshes with a gear 55 that is fixed to the end of a counter-shaft 56, journalled in bearings 57 provided for it in the case 20. To the end of the

counter-shaft which is opposite that to which the gear 55 is fixed is secured a pinion 58, which meshes with an internal gear 59 which is provided in the interior of the pulley rim 27.

Each individual of the train of gears 54, 55, 58, and 59, is accurately toothed, so that the said train of gears will operate with precision to import one complete revolution to the dial 51 in consequence of the movement of the dial plate 28 through one division of the zone 30 marked by next adjacent graduations 31.

It may be observed that while, in the machine illustrated, the graduations 31 indicate the travel of the bed-plates 6 in terms of inches, the distance between next adjacent graduations 31 is not necessarily an inch. It is practicable, therefore, to employ a dial plate 28 of such diametrical extent as will materially magnify the scale of the graduations on the zone 30 so that they may be easily read at a distance of ten feet or more from the eye of the observer. Indeed by sufficient enlargement of the diameter of the dial plate 28 the distance between the graduations 31 might be increased to such extent as to permit them to be divisible by lines visibly and clearly indicating fractional divisions of an inch; but, at best, the number of such fractional divisions so indicated is necessarily small, and the potential degree of enlargement of the dial plate 28 is quite restricted.

It is for that reason that we provide the fraction-indicating dial 51 having a definite rotational relationship to the dial plate 28, whereby movements of the log carriage may be registered in small fractional denominations. In the form of embodiment 100 of our invention, described for example, the dial 51 registers subdivisions of an inch divided into thirty-two parts, whereof each graduation mark 61 is separated from the next one in series by a space equal to or greater than the space between the graduations 31. It is therefore made as easy to read fractions of an inch in terms of thirty-seconds, as it is to read the indication of the integer, a pointer 63 being provided on the case 20, preferably at right angles to the location of the pointer 50, and extending in front of the face of the dial 51, across the zone 30, as shown in Figure I.

Referring now to the drawings, particularly to Figure I, it will be noted that the pointer 50 is in exact alignment with the graduation line 31 which is numbered "60". That is the indication that there are sixty inches of thickness of log on the bed plates 6 of the log carriage. Suppose that the first cut to be made therefrom is a board of an inch thickness. If the setter correctly sets the bed plates 6 the pointer must, after such setting, point, not exactly to the fifty- 120

ninth graduation but must register fifty-nine less a fraction to allow for the kerf of the saw.

It is obvious that such a fraction cannot be legibly registered on the zone 30 without the aid of the dial 51 or its equivalent, unless the length of the diameter thereof be at the least equal to say six feet or more, a length which is prohibitively great on account of the space it would occupy in a mill. For registering legibly very small fractions the length of the diameter must be greater.

While we have heretofore considered the dial 51 as making a single revolution, it is proper to observe that the said dial is not restricted in respect to the number of revolutions it may make in any single log-setting operation. It is obvious that, if the dial 51 makes one revolution for each inch of log-set, it will make two revolutions for two inches of log-set, and so on. Also a fraction of an inch of log-set will be registered both on the zone 30 as well as on the dial 51, its registry on the dial being, in effect, on a magnified scale which will facilitate the reading of it.

While the graduations 31 of the dial 28 indicate the approximate thickness of a log on the carriage, the fractional indicating dial 51 registers accurately the actual thickness of each board or cut from the log on a highly magnified scale. That is to say, whenever the log is set for the cut of a new board, the indication of the thickness of the board cut is indicated by the pointer 50, but it will be observed that the thickness of the board is legibly indicated with accuracy to the sawyer by the dial 51. Consequently, comparison of the indications on both dials will show the sawyer at a glance both the thickness of the cut and of the board last cut or being cut therefrom.

It should be furthermore observed that we use the term "dial" and "dial plate" herein in the broad sense of any plate between which and a pointer or index relative motion occurs, and without restriction to a circular or disk shaped plate. It is obvious, for instance, that the dial plate 28 and the dial 51 might be made stationary and that motion relative thereto might be imparted to the pointers 50 and 63, respectively; but while we regard such a variation as a potential modification of our invention, we deem the form of embodiment of our invention herein described to be obviously the preferable form.

Moreover, the direction of movement of the said dial or dial plate with reference to the said pointers, or contrariwise, is considered immaterial, and that reciprocatory or partial rotation may be substituted for the rotary motion which we describe and prefer at present to employ in respect to the elements indicated.

The operation of our device has been, in part, described in the foregoing specification, and will, it is believed, be rendered complete by the following summary of the result of said operation.

Let it be assumed that the dial plate 28 and the dial 51 occupy the relative positions in which they are illustrated in Figure 1. Those positions indicate that the thickness of the log on the log carriage is exactly sixty inches. Consequently, the pointer 50 registers exactly with the proper line 31 on the zone 30, and the pointer 63 is in exact alignment with the initial line of fractional indication on the dial 51.

If, now, for example, the sawyer signals the setter to set the log for the cut of a one inch board, and the setter makes a set which registers exactly 59 on the dial plate 28 and registers no fraction on the dial 51, the sawyer is informed thereby that the setter has committed the error of failing to make allowance for the kerf of the saw. He, therefore, holds the operation of the saw in abeyance until he shall have signalled the setter that error has been made in the log-set, and enabled him to correct it. It will appear upon consideration of the foregoing that by the aid of our invention, the chance of error in log-setting may be reduced in practice substantially to nil.

It should be observed, in respect to our indicator, that its operative connection is made directly with the knee itself of the log carriage, and registers the movement thereof independently of any mechanism by which the carriage is actuated. This is an important feature, because it often happens in practice that the carriage setting mechanism gets out of order without the knowledge of the setter. Our indicator, in such case, operates as a telltale to the sawyer, and, if upon his communication to the setter that the indicator shows an improper registry, the setter upon trial finds that the error is not of his making, the evidence that the fault is in the carriage setting mechanism is complete, thereby localizing and facilitating correction of the trouble.

What we claim is:

1. A sawyer's indicator for saw mill log carriages, having in combination a dial plate, a pointer carried in operative propinquity to the dial plate, a movable bed plate knee mounted on the carriage and means operatively connecting the knee to said dial for registering movement of the knee from a predetermined point.

2. In a sawyer's indicator for saw mill log carriages, the combination with an indicator case, a rotary dial plate thereon, and a pointer on said case, of a pulley rim on the dial plate, and flexible members secured at one end, respectively, to the pulley rim and winding upon it in opposite directions,

means for gravitationally actuating one of said members, and means operatively connecting the member to the knee of a bed plate of a saw mill carriage.

5 3. In a sawyer's indicator for saw mill log carriages, the combination with an indicator case, a rotary dial plate thereon, and pointers on said case, of a pulley rim on the dial plate, flexible members secured at one end, respectively, to the pulley rim and winding upon it in opposite directions, means for gravitationally actuating one of said members, and means operatively connecting the other member to the knee of a bed plate of a saw mill carriage, a fraction-indicating dial revolvably mounted on the indicator case, and a train of gears operatively connecting said dial and dial plate, respectively.

4. In a sawyer's indicator for saw mill log carriages, the combination with an indicator case, a rotary dial plate thereon, and pointers on the case, of a pulley rim on the dial plate, flexible members secured at one end, respectively, to the pulley rim and winding upon it in opposite directions, and means for gravitationally actuating one of said members, and means operatively connecting the other member to the knee of a bed plate of a saw mill carriage, a fraction-indicating dial revolvably mounted on the indicator case, and a train of gears operatively connecting said dial and dial plate, respectively.

5. In a sawyer's indicator for saw mill log carriages, the combination with an indicator case, a rotary dial plate thereon, and pointers on said case, of a pulley rim on the dial plate, flexible members secured at one end, respectively, to the pulley rim and winding upon it in opposite directions, means for gravitationally actuating one of said members, and means operatively connecting the other member to the knee of a bed plate of a saw mill carriage, a fraction-indicating dial revolvably mounted on the indicator case, and a train of gears operatively connecting said dial and dial plate, respectively, said pointers being disposed at right angles to each other, where the indication of each pointer is made clearly legible and without tendency to confuse the mind in the reading of them.

6. The combination with a log carriage having a part movable relative thereto, an indicator, and means operatively connecting the movable part with the indicator to register the thickness of an article on the carriage.

7. The combination with a saw mill carriage having a part movable relative thereto, an indicator, and means operatively connecting the movable part with the indicator to

automatically register the displacement of the movable part from a predetermined position and the thickness of a log on the carriage.

8. The combination with a movable log carriage, an indicator, and means operatively connecting said indicator to said movable log carriage to register the longitudinal displacement of the movable log carriage from a predetermined position and the thickness of an article associated with the movable log carriage.

9. The combination with a saw mill log carriage, of means mounted on the carriage for indicating the thickness of a log to be cut, and means operatively associated with said first mentioned means for registering fractional indications of the log being cut, said means being visible at points remote from the carriage.

10. In combination, a base having a movable member, of means operatively associated with the movable member for indicating the longitudinal displacement thereof from a predetermined position, said means comprising a revolvable main dial, and a concentric smaller dial for registering fractional parts of the main dial.

11. The combination with a saw mill carriage having a part movable relative thereto, an indicator dial, and means operatively connecting the movable part with the indicator dial to register the thickness of an article on the carriage, said indicator dial being legible at a distance of many feet from the carriage.

12. The combination with a saw mill carriage having a part movable relative thereto, an indicator for registering the displacement of the movable part from a predetermined position, said indicator comprising concentrically disposed dials, one of said dials arranged to register accurately the thickness of each board or cut from the log and the other the approximate thickness of the log.

13. The combination with a saw mill carriage having a part movable relative thereto, an indicator for registering the displacement of the movable part from a predetermined position, said indicator comprising an inner member and an outer member, one of said members arranged to register accurately the thickness of each board or cut from the log and the other member the approximate thickness of the log.

In testimony whereof, we have hereunto set our hands.

FIRN C. MAVIS.
GUY B. SAMPAIR.
